UNITED STATES PATENT OFFICE

FRANK M. MULRONEY, OF FORT DODGE, IOWA

GARMENT FASTENER

Application filed August 13, 1929. Serial No. 385,510.

This invention relates to fastening devices such as may be used for holding garments closed and the general object of the invention is to provide a device of this character which is very simple, which may be easily applied and whereby the overlapping edges of garments or articles of various character may be held closed with considerable force. My invention consists broadly speaking in the provision of a vacuum cup on one margin of the garment or other article and a "host" or element applied to the other margin of the garment with which the "guest" or vacuum cup will engage by suction or the provision of one vacuum cup which will act as a "host" and the other vacuum cup which will act as a "guest" as it may be termed, and which may be applied to the first named vacuum cup, these vacuum cups 20 adhering to each other by suction in the usual manner.

A further object is to provide a device of this character wherein the "host" or receiving member is in the form of a depression having a depth approximately equal to the thickness of the cloth to which the device is to be applied and the coacting "guest" member is capable of being inserted within this depression and engaged with the "host" 30 member or depressed member by the pressure of atmosphere.

Other objects will appear in the course of the following description.

My invention is illustrated in the accompanying drawings, wherein:—

Figure 1 is a sectional view through overlapping portions of a garment showing one form of my attachment device;

Figure 2 is a like view to Figure 1 but showing a slightly modified form;

Figures 3 and 4 show like views to Figures 1 and 2 but show modified forms of fasteners;

Figure 5 is a face view of the overlapping

portions of the garment showing my fastening device applied thereto;

Figure 6 is a section on the line 6—6 of Figure 5;

Figure 7 is a sectional view as in Figures 50 1 and 2 but showing another form of garment fastener;

Throughout this specification, I have used the term "host" member and "guest" member for the two elements of my attaching means as being explanatory of the fact that one receives the other and the two are held together by the suction primarily of the "guest" or detachably engaged member. As before stated, my invention consists broadly 55 in providing a "host" or receiving member upon one margin of a garment or article and providing a vacuum cup upon the other margin of the article adapted to be pressed against the receiving member so that the two margins will be engaged with each other 60 by the atmospheric pressure exerted upon the vacuum cup or cups.

In Figure 1, I illustrate a construction of this character wherein one margin of a garment which is designated A is provided with a rubber vacuum cup designated 10 held at its center to the margin A as for instance the margin of a piece of cloth or other fabric by means of the malleable metal clips 75 11 passing through a washer 12, the malleable clip extending through the body of the vacuum cup as at 13. The other margin of the garment designated B carries upon it a host or receiving member which, as illustrated in Figure 1, consists of a rigid flat disk 14 attached by malleable metal clips 80 15 to the margin B of the garment, there being a washer 16 disposed between the clips and the margin of the garment. This member 14 has preferably a slightly raised rim 85 and may have any desired form in plan, but is preferably larger in area than the area of the vacuum cup. Thus this disk may be round or may be square or it may be long- 90

tudinally extended so as to accommodate a plurality of these cups 10. Preferably the center of the disk 14 or "guest" element will be slightly depressed as at 17. It will be understood that in this form of the invention, the vacuum cup may be attached to the margin A by sewing, by vulcanizing, by metallic clips, or by any suitable means, this means, however, being preferably at the center of the vacuum cup as the margin of the vacuum cup must flex in order to properly engage the cup with the "host" member. The "host" member is preferably attached to the garment or other element B by devices which are disposed adjacent the margin of the "guest" member. The depression 17 at the central portion of the "host" member 14 will create a better vacuum area for the cups and a raised rim or edge at the disk 14 engages the extreme edges of the cup and centers the cup and thus prevents the cup from slipping off the rigid host 14.

In Figure 2, I have illustrated a "host" member which is rigid, but which combines two or more materials, as for instance, a back plate, 18 and a relatively soft face 19. In other words, in this form of my invention, I combine two or more materials to form the "host" element and in place of being constructed as described, this form of "host" element may be made of metal, bone, bakelite, or other rigid material with an enamelled, painted or varnished surface or a rubber surface.

In Figure 3, I illustrate another form of host in which the fabric C carries upon it a disk or "host" member 20, the middle portion of which is depressed as at 21, this depression extending over a relatively large area, that is, an area slightly greater than that of the vacuum cup or "guest", this depressed portion 21 having a depth approximately equal to the thickness of the fabric C. The vacuum cup under these circumstances, is inserted within this depressed portion or recess, this recess being large enough to permit the full depression of the vacuum cup and the corresponding expansion in area. The advantage of this construction is that it brings the two margins of the garment A and C more closely in conjunction with each other than is possible with the construction shown in Figure 2 or any other constructions which will be later described, as shown in Figure 4.

I do not wish to be limited to the means whereby this "host" element 20 is secured in place upon the garment or article, but preferably a washer-like member 22 will be disposed around the cup-shaped depression 21 and against the fabric and then the flange of the member 20 will be sewed, clipped, riveted or otherwise attached, the attaching means passing through the washer 22 and through the flat margin of the member 20.

In Figure 5, I have illustrated a construction wherein one margin D of the garment is provided with a "host" or receiving member 23 having the form of a more or less elongated strip attached to the garment as by vulcanizing, sewing, riveting, clipping or otherwise, this strip 23 having either a perfectly plane face or a rubber coated face as desired and having sufficient rigidity as to permit the vacuum cups 24 attached to the margin E of the garment to be applied against the receiving element or "host" 23 and retained thereon by suction. Preferably, and in order that the vacuum cups 24 may be disposed in proper position upon the strip 23 to hold the garment properly and in proper alinement, I mark or otherwise indicate upon the strip 23 colored rings 25 so that the wearer will know where the vacuum cups 24 should be indicated upon the member 23. This member 23 might be on raincoats, slickers and the like of relatively heavy rubber or of leather and in some garments, this might be a metallic strip either coated with rubber or uncoated but as indicated in Figure 5, I do not wish to be limited to the use of a specific "host" or receiving disk in connection with each vacuum cup, but the receiving element or "host" may be in the form of a strip more or less rigid upon which a plurality of vacuum cups may engage.

In Figure 7, I have illustrated another embodiment of my invention which is particularly good as a means for holding the overlapping margins of raincoats and the like closed and may be used in other situations, in which the receiving element or "host" consists not of a flat disk or strip, but of a vacuum cup designated 26^a and the "guest" element also consists of a vacuum cup 26, this being attached to the margins A and B of the garment in any suitable manner.

In this case, these cups are attached to the garment at their centers, leaving the edges of the disks free to be pressed against each other and form an air-tight contact. The principal advantage of this form of attachment lies in the fact that both complementary members are soft and flexible. In certain types of garments, as for instance, infants wear and some types of ladies' apparel, this softness would be of distinct advantage. In fact two rubber vacuum cups 26 designed to act as "host" and "guest" respectively could be used effectively in all cases where their softness would be an advantage and their bulk of thickness not be of disadvantage. In this type, the vacuum cup 26 or receptor is preferably larger than the element 26 in order to facilitate this engagement.

While I have before referred to the garment as having distinct "host" members or

receptors attached to the garment either in the form of strips, cups, disks or vacuum cups, I do not wish to be limited to this as some garments do not need these semi-rigid "hosts" or receptors, as for instance in articles or garments which are composed of heavy rubber composition and which have sufficient body and smooth surfaces, as for instance a belt or extra heavy rubber rain-coat. Vacuum cups could be placed on the inner side of the overlapping portion and the garment fastened by forcing the vacuum cups against the surface of the other margin, that is, just any place on the surface wherever the flap happened to fall. When used in this manner, there is a distinct advantage of fit as the wearer can fasten the garment to what-ever degree of fit is desired, either loose or tight.

In the case of a belt of heavy material with a smooth surface, the two ends of the belt could be engaged with each other by means of a vacuum cup or cups and a proper fit or tension could be obtained without punching any holes in the belt or otherwise mutilating it.

In my invention, there is always a certain amount of space taken up by the thickness of the two members in fastened position. In order that the two surfaces of the closed garment may be brought as closely together as possible, this thickness must be reduced to an absolute minimum. The greater stress on the "guest" element or suction cup is close to or at the central portion. This being the case, it is necessary to attach the "guest" element at or near its central portion, while with the receptor or "host" element, the greater stress is approximately at its rim. Therefore, the "host" is preferably attached to the garment at or slightly inward of its rim or edge. In this manner, the "host" element is held down tightly to the surface to which it is attached, which makes for the greatest possible thinness and brings the two surfaces of the overlapping portions in close proximity to each other.

Few, if any, garments have sufficient body in the material from which they are made to furnish a proper seat for a vacuum cup and I have discovered, therefore, that it is necessary in nearly all garments to provide a seat which will have sufficient rigidity or semi-rigidity to act as a "host" or receiver for the vacuum cup itself. Where disks are used as receivers or "hosts," they can be either vulcanized or sewed on to the garment. In garments which are made of fabric, as for instance, sweaters or cloth rain-coats the method of attaching these disks would be by sewing a thin rubber disk directly on to the garment and then vulcanizing a second disk on top of the one which is sewed to the garment.

This would seal up any holes which the sewing would cause. In the case of articles made of rubber composition as for instance, a relatively cheap traveling bag, the material used in the bag would be of the proper consistency to constitute a "host" but where the leather or composition was given a grain, that portion which would receive the vacuum cup would of necessity be left smooth. In addition to furnishing a satisfactory area for the "guest" cups to adhere to, the "host" member of my fastener designates or rather positions the point to which the "guest" or cup is to be fastened. In this manner, the garment is to be fastened in proper alinement. It will be seen that my invention furnishes a new type of garment fastener, adaptable to nearly all garments, and has certain distinctive advantages over anything now in use.

The rubber suction cups have been found by actual trial and tests to retain their suction action even when five years old and I have found that when a proper "host" member is provided for the suction cup to adhere to, that the cup will stay in fixed position against the "host" member practically indefinitely and that they will support a more or less constant strain for a long time. A proper "host" member is absolutely necessary as the vacuum cup cannot function properly and effectively in a situation ill-suited to it.

I claim:—

1. An article having overlapping portions, and means for holding the overlapping portions closed including a vacuum cup on one of said portions and a receiving member attached to the other portion and adapted to receive and afford a surface against which the vacuum cup will engage by suction.

2. An article having overlapping portions, a vacuum cup attached to the outermost of said portions and a receiving member attached to the confronting face of the other portion and adapted to receive the vacuum cup and having a surface against which the vacuum cup will engage and hold, said surface being larger than the vacuum cup.

3. The combination with overlapping portions of a flexible article, of a vacuum cup attached to one of said portions, and a relatively rigid receiving member attached to the other of said portions and having a surface with which the vacuum cup will engage, the receiving member being larger than the vacuum cup.

4. An article of apparel having two overlapping margins, means for holding said margins detachably closed comprising a vacuum cup mounted upon the inner face of one margin and a receiving member attached to the inner face of the other margin, the receiving member having a depressed center within which the vacuum cup

is received, the depression extending through the material of the article and said receiving member having a depth approximately equal to the thickness of the material.

5. An article of apparel having overlapping margins, and means for holding the margins closed comprising a vacuum cup attached to one of said margins and a receiving member attached to the other margin with which the cup is adapted to have suction engagement, the receiving member being larger than the diameter of the cup.

10 In testimony whereof I affix my signature.
